PARENTERAL COMPOSITION TO REDUCE DURATION OF LOCAL ANESTHESIA

Froilan P. Luduena, Albany, N.Y., assignor to Sterling Drug Inc., New York, N.Y., a corporation of Delaware

No Drawing. Application July 26, 1955
Serial No. 524,595

5 Claims. (Cl. 167—65)

This invention relates to a physiologically compatible solution adapted for parenteral administration to reduce the duration of vasoconstrictor-potentiated local anesthesia, comprising as essential ingredients an aminomethylbenzodioxan, adenosine and water.

In order to obtain rapid, intense and localized anesthesia, it has long been customary to administer with the local anesthetic a vasoconstrictor agent such as epinephrine, arterenol, phenylephrine or noradrenalin. The vasoconstrictor serves to inhibit the otherwise rapid systemic absorption of the local anesthetic.

A disturbing disadvantage of such local anesthetic solutions, however, is that complete or partial anesthesia persists too long after completion of the operative procedure for which it is needed. This unnecessary terminal anesthesia, for instance in dentistry, results in discomfort and annoyance to the patient in the form of an undesirable residual numbness of lips, cheeks, and sometimes also of the tongue. This undesirably long duration of anesthesia lasts from about two to four hours, or longer in some instances, the time depending on the particular anesthetic solution used.

The duration of anesthesia for a given anesthetic solution depends on the properties of each of the active ingredients, that is, the anesthetic agent and the vasoconstrictor. Attempts to decrease the duration of anesthesia have been made by searching for more potent, shorter-acting anesthetics. Limited success has been obtained in this direction by the introduction within the last decade of highly potent, short-acting anesthetics such as lidocaine and propoxycaine. However, use of these newer local anesthetics in vasoconstrictor-potentiated anesthetic solutions still results in a duration of anesthesia of about two to two and one-half hours or more. Attempts also have been made to decrease the duration of anesthesia by using an anesthetic solution having no vasoconstrictor; however, such a preparation has neither the required depth of anesthesia nor the necessary duration of anesthesia.

I have now found that this undesirably long duration of terminal anesthesia can be reduced greatly by administering parenterally at the site of the anesthetic injection a physiologically compatible solution comprising an aminomethylbenzodioxan and adenosine.

The effectiveness of my solution has been demonstrated by experimental tests in animals (guinea pigs) and confirmed in human subjects. My solution is administered by injection in the same location about fifteen to thirty minutes after the injection of the anesthetic solution or after the operation has been completed. In human patients, symptoms of anesthesia diminish rapidly almost immediately and disappear almost completely within about forty to ninety minutes.

By the term aminomethylbenzodioxan as used in this

2

specification, I refer to a type of compound well known to pharmacologists and having the structure

5

where $-N=B$ is an aliphatic type tertiary-amino group, such as piperidino, morpholino or diethylamino. The compound is preferably used in the form of the readily available hydrochloride but other acid addition salts can be employed if desired. I have had especially good results with the piperidino compound, piperoxan hydrochloride, but, for instance, the diethylamino compound, prosympal hydrochloride, can also be used.

The adenosine can be employed either as the simple adenine-riboside, or as one of the phosphate esters thereof such as the monophosphate or triphosphate.

20 To be physiologically compatible my new compositions are formulated to be reasonably near the osmotic pressure and pH of blood, and desirably the solutions should contain a buffer. Since the aminomethylbenzodioxan is most soluble and stable at acidic pH's, a practical 25 compromise must be effected. The operable pH range is about 3.5 to 7, with solutions having values within this range being stable and effective. Buffering agents can be utilized to adjust and maintain the pH within the operable range or within the preferred range of about 30 4 to 6.

As with the concentrations of the anesthetic agent and the vasoconstrictor of injectable local anesthetic solutions, the concentrations of the aminomethylbenzodioxan and adenosine of my solution should be kept preferably 35 at a minimum effective level. Preferred embodiments of my invention contain about 0.01 to 0.50% (weight per volume) of piperoxan, preferably in the form of its hydrochloride, about 0.10 to 0.30% (weight per volume)

40 of adenosine, and enough sodium chloride to make the solution isotonic. Optimum concentrations are about 0.05 to 0.10% of piperoxan and about 0.20% adenosine. The following examples will illustrate the specific embodiments of my invention without, however, limiting it thereto. All percentages given hereinbelow and in the 45 claims are in terms of weight per volume, e.g., grams per cc.

Example 1

Solutions were prepared by mixing well the following ingredients:

	1A	1B
Piperoxan hydrochloride.....	g. 0.050	g. 0.025
Adenosine.....	g. 0.20	g. 0.20
55 Sodium chloride.....	g. 0.85	g. 0.85
Distilled water, q.s.ad.....	cc. 100.00	cc. 100.00

A series of experiments were carried out using guinea pigs that showed the effectiveness of solutions of my invention, such as solutions 1A and 1B given above, in reducing greatly the duration of anesthesia produced by the injection of a vasoconstrictor-potentiated local anesthetic solution. The solutions were injected about 60 twenty minutes after the injection of the anesthetic solution. The solutions were administered either intradermally or subcutaneously; and the duration of anesthesia was determined by the technique of Bulbring and Wajda [J. Pharmacol. and Exp. Therap. 85, 78 (1945)].

Using this method, the times necessary to reduce anesthesia to three-fourths, one-half, and one-fourth of the maximal value were determined. The relative effectiveness of solutions of varied composition was determined in this manner. The following table shows the relative effectiveness of my above solution 1B (experiment II) and a solution containing only sodium chloride (experiment I). The anesthetic solution used (0.25 cc. for each injection) contained propoxycaine hydrochloride (0.4%), procaine hydrochloride (2.0%) and levo-arterenol (1:30,000).

Experiment	Second Injection *		Volume Injected (cc.)	Average Duration of Anesthesia After Second Injection (minutes)			
	Solution	Conc. Percent wt./vol.		Percent Anesthesia			
				75	50	25	
I b	Saline	0.85	0.50	117	140	180	
II	Piperoxan HCl and Adenosine	{ 0.025 0.20 }	0.50	23	26	30	

* Administered intradermally.

b Accumulation of data from a number of experiments involving 56 guinea pigs.

0.85% NaCl.

From the data of the above table, it is seen that the solution 1B (containing 0.025% piperoxan HCl, 0.20% adenosine and 0.85% NaCl) produces a marked reduction in terminal anesthesia. Comparable results were obtained with my solution 1B when administered subcutaneously.

My solution 1A, which contains twice the amount of piperoxan HCl as solution 1B, produced about the same effect as solution 1B in reducing the duration of anesthesia.

Example 2

Solutions of my invention were prepared by mixing well the following ingredients:

	2A	2B
Piperoxan HCl	g. 1.00	1.00
Adenosine	g. 4.00	4.00
Sodium Lactate	cc. 400	720
Lactic Acid	cc. 400	80
Distilled water, q.s. ad.	cc. 2,000	2,000
pH when compounded	4.0	4.85

Solutions 2A and 2B were filtered into 2.2 cc. cartridges through a sterilizing filter.

Solution 2B was administered to human subjects to establish its effectiveness in shortening the duration of dental anesthesia as follows: Four subjects were given bilateral mandibular injections of 2.0 cc. each of a local anesthetic solution containing propoxycaine hydrochloride (0.4%), procaine hydrochloride (2.0%) and 3,4-dihydroxyphenoxyphrine hydrochloride (1:10,000), each injection being made at a rate of 1 cc. per minute. A full cartridge of solution 2B (2.2 cc.) was then injected in each subject in the same location, on the right side only, about fifteen minutes after the onset of symptoms of anesthesia. After the injection of solution 2B, the symptoms of anesthesia started to regress rapidly and within thirty-eight minutes from the time solution 2B was injected, sensations had returned to the teeth on the right side in all cases. All symptoms of anesthesia ceased in the right side after about ninety-six minutes. In the left side, sensation returned to the teeth after about one hundred and fifty minutes and all symptoms disappeared after about one hundred and ninety-five minutes. No unpleasant local symptoms were reported during or after the second injection. Also, no systemic effects and no postoperative signs of irritation were observed.

Example 3

Solutions within the scope of my invention having pH values between about 4.0 and about 5.0 were prepared by mixing well the following ingredients:

		3A	3B	3C
10	Piperoxan Hydrochloride	g. 0.05	0.05	0.05
	Adenosine	g. 0.20	0.20	0.20
	Citric Acid	g. 0.40	0.40	0.20
	Sodium Citrate	g. 0.40	0.60	0.80
	Sodium Chloride	g. 0.60	0.54	0.51
	Distilled Water, q.s. ad.	cc. 100.00	100.00	100.00
	pH	4.05	4.45	5.0

15 Solutions 3A, 3B and 3C were filled into 2 cc. flint ampuls and in each case half the batch was heated at 121° C. for fifteen minutes and the other half was not heated.

These solutions showed excellent stability on storage, even at 37° C.

Example 4

Solutions having pH values between about 5.5 and about 7.0 were prepared by mixing well the following ingredients:

		4A	4B	4C	4D
30	Piperoxan HCl	g. 0.05	0.05	0.05	0.05
	Adenosine	g. 0.20	0.20	0.20	0.20
	Na ₂ HPO ₄ ·12H ₂ O	g. 0.20	0.45	0.75	0.90
	Na ₂ HPO ₄ ·H ₂ O	g. 0.80	0.30	0.20	0.10
	Sodium Chloride	g. 0.39	0.55	0.52	0.53
	Distilled Water, q.s. ad.	cc. 100.00	100.00	100.00	100.00
	pH	5.5	6.0	6.5	7.0

35 Solutions 4A, 4B, 4C and 4D were filled into 2 cc. flint ampuls and in each case half the batch was heated at 121° C. for fifteen minutes and the other half was not heated.

These solutions showed excellent stability on storage even at 37° C.

Example 5

Solutions were prepared by mixing well the following ingredients:

		5A	5B
45	Piperoxan hydrochloride	g. 0.025	0.025
	Adenosine-5-monophosphate	g. 0.20	-----
	Adenosine triphosphate	g. -----	0.10
	Sodium chloride	g. 0.85	0.85
	Distilled Water, q.s. ad.	cc. 100.00	100.00

50 The effectiveness of solutions 5A and 5B in reducing the duration of anesthesia produced by the injection of a vasoconstrictor-potentiated local anesthetic solution was determined using guinea pigs following the procedure given in Example 1. The results are presented in the following table:

Experiment	Second Injection *		Volume Injected (cc.)	Average Duration of Anesthesia After Second Injection (minutes)			
	Solution	Conc. percent wt./vol.		Percent Anesthesia			
				75	50	25	
Ib	Saline	0.85	0.50	117	140	180	
II	Piperoxan HCl and Adenosine	{ 0.025 0.20 }	0.50	19	27	49	
III	Piperoxan HCl and Adenosine triphosphate	{ 0.025 0.10 }	0.50	29	37	50	

* Administered intradermally.

55 b Accumulation of data from a number of experiments involving 56 guinea pigs.

0.85% NaCl.

I claim:

1. A physiologically compatible solution adapted for parenteral administration to reduce the duration of vasoconstrictor-potentiated local anesthesia comprising as essential ingredients about 0.01 to 0.50% of an amino-methylbenzodioxan selected from the group consisting of 2-(1-piperidylmethyl)-1,4-benzodioxan, 2-(diethylamino-methyl)-1,4-benzodioxan and acid-addition salts thereof, about 0.10 to 0.30% of a compound selected from the group consisting of adenosine and a monophosphate ester thereof, and water, said solution having a pH range of about 3.5 to 7.

2. A physiologically compatible solution adapted for parenteral administration to reduce the duration of vasoconstrictor-potentiated local anesthesia comprising about 0.01 to 0.50% of piperoxan hydrochloride, about 0.10 to 0.30% of adenosine and water, said solution having a pH range of about 3.5 to 7.

3. A physiologically compatible solution adapted for parenteral administration to reduce the duration of vasoconstrictor-potentiated local anesthesia comprising about 0.05 to 0.10% of piperoxan hydrochloride, about 0.20% of adenosine, water and enough sodium chloride to make the solution isotonic, said solution having a pH range of about 3.5 to 7.

4. A physiologically compatible solution adapted for

5
10

parenteral administration to reduce the duration of vasoconstrictor-potentiated local anesthesia comprising about 0.05% of piperoxan hydrochloride, about 0.20% of adenosine, water, a buffering agent to maintain the pH within the range of about 4.0 to about 6.0 and enough sodium chloride to make the solution isotonic.

5. A physiologically compatible solution adapted for parenteral administration to reduce the duration of vasoconstrictor-potentiated local anesthesia comprising about 0.01 to 0.50% of piperoxan hydrochloride, about 0.10 to 0.30% of adenosine, water and a buffering agent to maintain the pH within the range of about 3.5 to 7.
